(57) **CLAIM**

The ornamental design for a lamp, as shown and described.

DESCRIPTION

FIG. 1 is a bottom, front and right side perspective view of a lamp showing our new design;
FIG. 2 is a front elevational view thereof;
FIG. 3 is a rear elevational view thereof;
FIG. 4 is a right side view thereof;
FIG. 5 is a left side view thereof;
FIG. 6 is a bottom plan view thereof;
FIG. 7 is a top plan view thereof;
FIG. 8 is a top, rear and left side perspective view thereof;
and,
FIG. 9 is an enlarged view of portion 9 in FIG. 1.

The lamp is shown with symbolic breaks. The appearance of any portion of the article between the break lines forms no parts of the claimed design.

1 Claim, 9 Drawing Sheets
